PORTABLE POWER-OPERATED IMPACT WRENCH

Marnie C. Averitt, 107 Westdale Court, Timonium, Md.

Original design application Oct. 18, 1965, Ser. No. 87,581,
now Patent No. 205,091, dated June 21, 1966. Di-
vided and this application Apr. 26, 1966, Ser. No. 2,024

Term of patent 14 years

(Cl. D54—14)

FIG. 1

FIG. 2

FIG. 3FIG. 4FIG. 5FIGURE 1 is a side elevation of the portable power-operated impact wrench;

FIGURE 2 is a top plan view of the impact wrench shown in FIGURE 1;

FIGURE 3 is a rear elevation;

FIGURE 4 is a front elevation; and

FIGURE 5 is a bottom plan view.

This application is a divisional application of my previously filed application, Ser. No. D. 87,581, entitled "Portable Power-Operated Impact Wrench," filed Oct. 18, 1965, and now Patent Serial No. D. 205,091.

The broken line showing of the tool adapter element has been omitted in FIGS. 2, 4 and 5 for convenience of illustration only.

The dominant features of my design reside in the portions shown in full lines.

I claim:

The ornamental design of a portable power-operated impact wrench, as shown and described.
